UNITED STATES PATENT OFFICE.

JOHN R. LONG, OF AKRON, OHIO.

MEANS FOR REAMING AND THREADING PIPES.

1,160,625.

Specification of Letters Patent. Patented Nov. 16, 1915.

Application filed November 22, 1912, Serial No. 732,858. Renewed September 18, 1915. Serial No. 51,408.

To all whom it may concern:

Be it known that I, JOHN R. LONG, a citizen of the United States, residing at Akron, in the county of Summit and State of Ohio, have invented certain new and useful Improvements in Means for Reaming and Threading Pipes, of which the following is a specification.

This invention appertains to means for reaming and threading pipes, and the invention consists in the novel construction and arrangement of parts whereby a cutting tool may be mounted for end movement in respect to the pipe by a device adapted to engage within the pipe all substantially as shown and described and particularly pointed out in the claims.

In the accompanying drawings, Figure 1 is a side elevation of a reamer and anchor combined, and Fig. 2 is a longitudinal section of a pipe with my anchor engaged therein. Fig. 3 is a similar view of the anchor alone in a smaller pipe than shown in Fig. 2, and Fig. 4 is a similar view of a larger pipe and the anchor therein but with the jaws in a different position in the spreading head from that shown in the preceding views and as hereinafter described. Fig. 5 is a front perspective view of the jaw carrying head, and Figs. 6 and 7 are sectional elevations thereof on different lines. Fig. 8 is a perspective view of one of the two jaws. Figs. 9 and 10 are side elevations of the reaming or cutting tool from different points of view, and Fig. 11 is an end view showing the smaller end of the tool. Fig. 12 is a sectional side view and elevation of a modification of the invention.

As thus shown the plan of the invention is to anchor the reamer or reaming tool or other cutter in or on the pipe to be reamed, and the anchor is adapted to work in pipes of various sizes, from the minimum in Fig. 3, to the maximum in Fig. 4. Thus in Figs. 1 to 11 I show a device consisting in a tube 2 which has an external thread 3 at its outer end and carries the jaw adjusting or spreading head 4 on its inner end. The reaming tool 5 will be seen to be original and peculiar in shape in this particular, that it is an open member which by reason of its construction as shown, can be drop-forged and thus made comparatively cheap from a manufacturing point of view and yet serve all the purposes of a reamer for a plumber who takes the tool

out on a job and really does not require as elaborate or expensive a tool as is usually provided for factory work. Hence I have made the present tool which has opposite cutting blades or ribs *m* conically disposed as in such cutters usually and united at or within the point by a collar shaped integral connection *n* and provided with a head or base portion *o* having an internal thread by means of which the said tool is mounted upon its support 6. Otherwise the mechanism shown has to do with feeding said head and tool forward under spring pressure as reaming proceeds, and comprises a follower 8 with a wheel or handle to rotate the same and bearing against a suitably heavy spiral spring 7 in the hub of head 6 and which presses against the said reamer to feed the same along under spring pressure while it is being rotated through head 6.

The anchoring means comprises a head 4 as described which is mounted or socketed on the end of tube 2, and an adjusting rod or tube 10 passes lengthwise through said tube 2 and has a collar 12 within the angularly enlarged end thereof bearing against said head 4 while the inner extremity *a* of said rod is threaded and carries the adjusting nut 14 which supports the jaws 15. The said nut is threaded to be run back and forth on the thread *a* according to the size of the pipe in which it is located for the time and the spread the jaws are to receive therein, and said jaws are pivotally mounted between the ears *b* on the said nut and adapted to work in the transverse slots or recesses *c* and *d* respectively in the said head 4. For pipes of the smaller or medium sizes the said jaws are engaged in the inclined slots 15, and for larger sizes, as Fig. 4, they are engaged in the recesses or slots *d* in which the right angled shoulders or walls *g* take the place of said inclines *f* and throw the jaws out at a more direct angle, as seen in Fig. 4. The said jaws are supported on pivot pins in said recesses and have springs *s* to press them inward, normally, and are provided with teeth *h* at their outer ends arranged more or less in a circle so as to make biting engagement with the interior wall of the pipe in any position of adjustment. A dowel pin 20 or its equivalent serves to limit the open or outer position of the nut 14 and beyond which it need not be moved to accommodate itself and jaws 15 to the smallest

pipe, and the adjustments are from this point inward as larger pipes are needed. Adjustment of the said jaws and the nut 14 is through the rod 10 which carries the 5 nut, and a suitable head 22 is fixed on the end of said rod and provided with a handle 23 to turn the same. This or equivalent means may be employed for this purpose. Thus it will be seen that the follower 8 10 runs on sleeve 2 and serves through the intervening spring to press the reamer forward under spring pressure, while the rotatable head 6 which has the reamer fixed thereon serves to actuate the same and do 15 the reaming. Of course in the use of the reamer the first step is to get it anchored in the right position in the pipe. This being done by effectively engaging the jaws 15 in the pipe P preparatory to setting the 20 other parts, the follower 8 is next turned to press the cutter or reamer 5 to cutting position. In this operation the said reamer is placed under spring pressure as above described. Then the parts are in readiness to 25 begin the reaming and the said spring keeps the reamer at work under the requisite pressure as the work proceeds. When done the jaws 15 are released and the entire device is withdrawn.

3. My inventive concept also includes the arrangement and construction of parts shown in Fig. 12, whereby a die stock of common form may be substituted for the reamer shown in the other figures. In the larger 35 sizes of pipe it is exceedingly difficult to start threading operations and also to complete such operations, but with the aid of my improved device, such operations are more easily and efficiently accomplished. Thus, as 40 shown, a die stock 25 is mounted upon the end of a piece of pipe P in a starting position to provide the same with an exterior thread. The die stock is held in this position under more or less pressure applied by 45 the follower 8 threaded on sleeve 2 of the anchoring device, a loose bearing washer 26 being interposed between the die stock and said follower and adapted to press the said stock forward into threading position. The edges of the cutting jaws of said 50 stock are beveled to make the ascent easy, and when the initial or lead thread has

been cut the said stock will feed itself and all the other portions of the device are removed and the stock is left to complete its 55 work in the usual way.

What I claim is:

1. In devices for fixing cutting tools on pipes, an anchor comprising a rotatable screw-rod, a nut on said rod and anchoring 60 jaws pivoted on said nut and free at their outer ends, in combination with a tapered head adapted to spread said jaws having recesses in which said jaws are slidable to spread into engaging position, a tube sleeved 65 over said rod and having said head fixed on its outer end, and means to turn said rod independently of said tube and thus feed said nut and spread the jaws.

2. In devices for securing cutting tools 70 in working position on a pipe, an anchor comprising a head having recesses axially inclined and a tube on which said head is mounted, a rod extending through said tube and head having a threaded end, a nut 75 mounted on said threaded end and a set of anchoring jaws pivoted on said nut and resting in said recesses, the said rod having a collar fixed thereon within said head to prevent axial movement of the rod when rotated, and springs in said head bearing on 80 said jaws to press the same inward.

3. A device for fixing cutting tools in pipes comprising a tube and a head fixed on 85 one end thereof having radially disposed recesses inclined to the axis of said tube, in combination with a rod through said tube and head having a threaded end, a nut mounted on said threaded end and pipe engaging jaws pivoted thereon and resting in 90 said recesses, means to rotate said rod and thus thrust said jaws into engaging and disengaging positions, a pipe reamer having inclined cutting ribs rotatably mounted on 95 said tube, means to rotate said reamer and a spring in the reamer to feed the same along when at work.

In testimony whereof I affix my signature in presence of two witnesses.

JOHN R. LONG.
